SNAP SWITCH

William H. Hollinshead, St. Paul, Minn.

Application November 4, 1948, Serial No. 58,261

1 Claim. (Cl. 200—68)

1

My invention relates to an improvement in snap switch wherein it is desired to provide a simple and inexpensive switch for closing one or a plurality of contacts.

Snap switches are sometimes employed for controlling the operation of mechanism which is subjected to the elements. For example, in the control of pumping mechanism where the operation of the pump depends upon fluid level, it is desirable to provide a snap switch which may be operated easily by a float or similar apparatus, but which at the same time may be made at a minimum cost. With such devices it is desirable that the mechanism be water resistant and that the contacts and contact points be protected from moisture. Thus short circuiting between the switch terminals is prevented.

It is the object of the present invention to provide a snap switch which operates with little difficulty and which at the same time may be made at a low cost of production. The parts of my device are so constructed that they may be easily assembled and when once in place, will remain in proper assembled form.

A feature of the present invention lies in the provision of a snap switch having a plurality of contacts mounted in spaced relation upon a single insulation panel which is supported toward the upper end of the casing. The mechanism for actuating the contacts is all located below the level of the insulated panel in such a way that even though moisture entered the lower portion of the casing, the contacts and terminals would be protected. As a result, the switch may be used out of doors or exposed to dampness and moisture with little danger of short circuiting.

A feature of the present invention lies in the provision of a casing having an open top and an open front and in providing an integral covering panel which extends over both the top and front of the casing to enclose the same. This covering panel is provided with marginal flanges which extend partially over the back panel and over the side wall panels so as to form a closure therefor.

An added feature of the present invention lies in the provision of a shield which covers the opening in the casing through which the contact wires extend, this shield extending downwardly and being open at the bottom to act as a baffle to prevent moisture from entering the upper portion of the casing.

These and other objects and novel features of my invention will be more clearly and fully set forth in the following specification and claim.

In the drawings forming a part of my specification, Figure 1 is a front elevational view of my switch showing the construction thereof.

Figure 2 is an elevational view of one side of

the switch showing the conductor extending into the casing.

Figure 3 is an elevational view of the opposite side of the casing from that illustrated in Figure 2, a portion of the casing being broken away to indicate the manner in which the insulation panel is supported.

Figure 4 is a sectional view through the switch mechanism showing the contacts in open position.

Figure 5 is a view similar to Figure 4 showing the contacts in closed position.

Figure 6 is a plan view of the contact operating mechanism attached to the bottom panel of the casing.

Figure 7 is a top plan view of the insulation panel with the terminals connected thereto.

Figure 8 is a side elevational view of the operating lever for operating the switch mechanism shown in Figure 6.

Figure 9 is a sectional view through the switch lever, the position of the section being indicated by the line 9—9 of Figure 6.

Figure 10 is a perspective view of one of the casing sections.

The snap switch A includes a housing which includes three main portions. One such portion, indicated in general by the numeral 10, includes a back wall panel 11 and a pair of substantially parallel side wall panels 12 and 13. The back wall panel 11 includes an elongated offset portion 14 which is pressed rearwardly on to a plane spaced from the plane of the back panel 11 and generally parallel thereto. This recessed portion 14 permits the casing to be secured snugly against a suitable supporting element as will be later described in detail.

The side wall panels 12 and 13 are provided with rounded corners 15 and 16 respectively at the juncture of the upper edges of the panels and the forward edges thereof. The side panel 13 is provided with an elongated notch 17 therein at the juncture of the forward edge of the panel and the lower edge 19 thereof.

A second portion of the casing is illustrated in Figure 10 of the drawings, and is indicated in general by the numeral 20. The casing member 20 includes a bottom panel 21, parallel side wall panels 22 and 23 and a front wall flange 24.

The side wall panels 22 and 23 are spaced apart a distance just sufficient to fit within the parallel side wall panels 23 of the casing section 10. The front wall flange 24 extends upwardly substantially flush with the forward edges of the parallel walls 22 and 23 and is designed to lie inwardly of the cover section of the casing, not yet described in detail.

A cap screw or metal screw 25 extends through the outer side wall panel 13 and is threaded into the side wall panel 23 of the second casing section

to hold these walls in parallel contacting relationship. A pair of spaced cap screws or metal screws 26 extend through the side wall panel 12 and are threaded into the wall panel 22 to fasten the panels 12 and 22 in parallel contacting relation. The screws 26 also serve to hold the conductor shield 27 in place against the wall panel 12.

The shield 27 is provided with a marginal flange 29 which is on a flat plane. An outwardly bulged center portion 30 is drawn from the sheet forming the shield so as to form a passage for containing the electrical cable or conductor. Thus the shield 27 fits flat against the wall panel 12 and is sealed thereagainst along its upper edge and side edges, while the central outwardly bulged portion 30 is opened at its lower end. A pair of parallel slots 31 are provided communicating with the lower end of the flanged edge 29 to accommodate the screws 26.

The third main portion of the housing is indicated by the numeral 32 and forms a removable cover or closure for the casing. The member 32 includes a front panel 33 and a top panel 34 connected by a rounded portion 35. Flanges 36 and 37 are provided on the cover section 32, these flanges partially overlying the side walls 12 and 13 near the front and top free edges to form an overlapping connection between the front closure panel and the other part of the casing. A rear flange 39 overlies a portion of the rear wall 11 of the enclosure so as to form an overlapping connection with the rear casing wall. A slot 40 is provided communicating with the lower edge of the front wall panel 32 and a metal screw or cap screw 41 extends through the slot 40 and is threaded into the front flange 24 of the second casing section so as to hold the cover firmly in place.

It will be noted that because of the flanges 36, 37 and 39, the cover panel 32 must be raised upwardly from the remainder of the casing until it is clear of the side walls of the casing and until the slot 40 is clear over the screw 41. When the cover panel is in place, moisture dropping upon the casing will drain down the side walls and cannot readily enter the upper portion of the casing.

As indicated in Figures 3 and 10 of the drawings, an elongated transverse aperture is provided in each of the side walls 22 of the casing section 20. One such aperture 42 is provided in the side wall 22 and a second aperture 43 is provided in the side wall 23. If desired, notches 44 and 45 respectively may communicate with the central portions of the apertures 42 and with the upper edge of the side walls so as to simplify the removal of the punched out portion of the stock in the apertures.

An insulation panel 46 is supported by the apertures 42 and 43. The insulation panel is of proper length to fit snugly between the casing walls 22 and 23 and as illustrated in Figure 7 of the drawings, projecting lips or ears 47 and 49 are provided at opposite ends of the panel, these ears entering the apertures 42 and 43. Thus when the insulation panel 46 is in place, it is held between the walls 22 and 23 with the screws, bolts, or other fastening means, the panel merely being held in place by the lips or ears 47 or 49 at opposite ends thereof.

A pair of spaced terminal plates 50 and 51 overlie the top surface of the panel 46 in aligned relation. A second pair of contact plates 52 and 53 are similarly aligned in spaced relation to the plates 50 and 51. Contact terminals 54 and 55 extend through the spaced plates 50 and 52 to

hold these plates in fixed relation to the mounted panel. These contacts 54 and 55 are provided with enlarged downwardly projecting heads 56 which form contact points. The plates 51 and 53 are held in place upon the insulation panel 46 by contact rivets 57 and 59. These rivets 57 and 59 also act to support spring contact strips 60 in parallel relation on the under surface of the insulation block 46. The spring contact strips 60 are provided with contact buttons or heads 61 which are engageable with the enlarged heads 56 of the contacts 54 and 55. The spring of the strips 60 normally holds the contacting ends 61 in spaced relation from the contact heads 56. However, the spring strips are so designed that the contacting ends thereof may be sprung into engagement with the corresponding terminals on the plate as indicated in Figure 5 of the drawings.

The snap switch mechanism is best illustrated in Figures 4, 5 and 6 of the drawings. The mechanism is indicated in general by the numeral 62. This mechanism is mounted upon a supporting frame including a bottom plate 63 which overlies and rests upon the bottom plate 21 of the casing section 20 and a pair of parallel upright mechanism supports 64 and 65. The mechanism supports 64 and 65 are formed as best illustrated in Figure 4 of the drawings, each including a pair of spaced upright arms 66 and 67 which are provided with notches 69 and 70 along their inner edges. The notch 69 in the arm 66 is designed to pivotally support the operating lever in a manner which will be later described, while the notch 70 is designed to pivotally support the contact operating lever.

With reference to Figure 6 of the drawings, it will be noted that the operating lever 71 extends through the notch 70 in the side wall 13 of the casing and extends along side of the upright portion 65 of the snap switch support. The lever 71 is provided with a cross arm 72 which rearwardly extends in the casing and supports a longitudinally extending lever end 73 parallel to the portion of the lever 71 extending through the casing wall. The lever 71 includes a pair of inturned opposed ears 74 and 75 which extend toward each other and engage in the notches 69 in the arms 66. These ears 74 and 75 thus act as fulcrums for the lever 71 and engage in the parallel notches 69.

The snap switch contact strip actuating lever 76 extends between the upright portions 64 and 65 and is provided with outwardly extending ears 77 which engage in the notches 70 in the upright arms 67. The notches 70 act as fulcrums for the opposed pivot ears 77 of the lever 76. The lever 76 is provided with a central notch 79 which extends through the major portion of the length of the lever. A spring 80 is connected to the lever 76 near one end of the notch 79 and is centrally connected to the cross connecting arm 72 of the lever 71 to hold these levers engaged against their respective fulcrums. In other words, the spring 80 serves the double purpose of actuating the lever 76 in a manner which will be later described and also holds the lever 71 engaged in the notches 69 and holds the fulcrums of lever 76 engaged in the notches 70.

The lever 76 is provided with an upturned flange end 81 thereupon to which is secured a strip 82 of insulating material. This insulating material is pivotal against the under surface of the contact strips 60 so as to urge the contact ends 61 thereof against the fixed contact heads 56. In one ex-

treme position of the lever 76 illustrated in Figure 4 of the drawings, the insulation strip 82 permits the spring contact strips to be operated from their respective fixed contacts. In the other extreme position illustrated in Figure 5 of the drawings, the spring arms are engaged against their respective contacts.

Pivotal movement of the lever 71 is limited by engagement of the cross connecting arm 72 with laterally extending projections 83 and 84 on the arms 67. In one extreme position of the lever 71 the cross connecting arm 72 is in engagement with the projections 84. In the other extreme position the cross connecting member 72 is in connection with the projections 83.

Pivotal movement of the lever 76 is similarly effected by projections 85 and 86 on the arms 66. Ears 87 on the lever 76 are engageable in one extreme position with the projections 85 and in the other extreme position with the projections 86. Thus the supporting frame of the snap switch mechanism not only supports the two levers but acts to limit their movement. It will be noted that when the lever 71 is in its lowered position, the cross connecting member 72 of the lever is in engagement with the projections 84. When the contacts are to be closed, the lever 71 is swung in a clock-wise direction as viewed in Figures 1, 4 and 5 about the fulcrum notches 69 until the spring 80 is aligned with the major portion of the lever 76. As soon as the spring 80 moves past alignment with the lever 76, the spring 80 pivots the lever 76 in a clock-wise direction about its fulcrum notches 70 swinging the insulation block 82 against the spaced contact strips 60 and urging them against their corresponding fixed contacts. The opening of the contacts is accomplished by a reversal of this process. The lever 71 is lowered until the spring 80 passes alignment with the body portion of the lever 76 whereupon the lever 76 pivots about its fulcrum notches 70 in a counter-clockwise direction to its opposite extreme position. The insulation block 82 is moved away from the spring plates 60 allowing these plates to spring into the open position shown in Figure 4 of the drawings.

The assembly of my switch is extremely simple. The levers 76 and 72 are connected by the spring 80 and forced into the space between the arms 66 and 67, the spring holding the two levers thus assembled. The supporting base 63 of the snap switch mechanism is held to the bottom panel 21 of the casing section 20 by cap screws or metal screws 90. The contact plates of Figure 7 are secured to the insulation panel 46, the connecting rivets also securing the fixed contacts and the spring contact strips in place. The insulation panel 46 is then sprung between the parallel sides 22 and 23 of the casing section 20.

The casing section 20 is then secured to the casing section 10 by the bolts or cap screws 25 and 26, the latter screws also securing the shield 29. The cover section 32 is then slid downwardly over the body of the device and secured thereto by the single clamping screw 41.

When the cover portion 32 of the casing is removed, the terminals are readily accessible and the terminal cables may be connected thereto. The switch casing is usually supported by some support such as 91 which has an opening 92 therein for accommodating one cable 93. The other cable extends through an aperture 94 in the casing wall 12 aligned with the interior of the shield 27 and this cable 95 extends downwardly through the shield 27 and is protected.

The casing may be secured to the fixed support 91 by screws or bolts 96 which extend through apertures 97 and 99 in the offset portion 14 of the casing panel 11. The offset portion 14 fits snugly against the support 91 and holds the remainder of the panel 11 slightly spaced from the support so that the flange 39 of the closure panel may extend rearwardly of the back panel 11.

The operating lever 71 is preferably provided through at least a portion of its length with a reinforcing flange 100 which extends along one edge thereof. A hole 101 may be provided in the lever 71 so that this lever may be easily attached to an operating arm for action by a float or similar device.

In accordance with the patent statutes I have described the principles of construction and operation of my snap switch, and while I have endeavored to set forth the best embodiment thereof, I desire to have it understood that obvious changes may be made within the scope of the following claim without departing from the spirit of my invention.

I claim:

A snap switch including a support having a base and a pair of substantially parallel side plates, each of said side plates being divided to form two spaced arms, the arms of one side plate being opposed to the arms on the other side plate and forming two pairs of opposed spaced arms, each pair of arms having a notch on their inner surface directed toward the other pair of arms and at least one arm of each pair of arms having a pair of spaced ears on its outer surface, a yoke shaped lever including spaced sides extending outwardly of said side plates and being connected along one end thereof, said sides having inwardly extending projections engageable in the notches of one pair of arms, a second lever extending between said side plates and including outwardly directed projections engageable with the notches of the other pair of arms, said second lever having a center slot therein, a spring secured to the connecting member of said first lever and extending through the slot of said second lever and connected to said second lever, means for pivoting one of said levers beyond alignment with the other of said levers, said spring acting to pivot the other of said levers as the pivoted lever moves past aligned position, an angularly extending arm on the other of said levers, and circuit closing means positioned for actuation by said angularly extending arm, portions of said levers abutting said spaced ears to limit the respective pivoting of said levers through an arc determined by the spacing of said ears.

WILLIAM H. HOLLINSHEAD.
